(57) **CLAIM**

The ornamental design for a hook rack, as shown and
described.

DESCRIPTION

FIG. 1 is a top front and right side perspective view of a first
embodiment of a hook rack showing our new design;

FIG. 2 is a top plan view thereof;

FIG. 3 is a front elevational view thereof;

FIG. 4 is an enlarged cross-sectional view thereof, taken
through FIG. 3 at line 4-4;

FIG. 5 is a right side elevational view thereof;

FIG. 6 is a bottom plan view thereof;

FIG. 7 is a rear elevational view thereof;

FIG. 8 is a left side elevational view thereof; and,

FIG. 9 is a second embodiment of a hook rack, which is the
same as the first embodiment except for the cross-sectional
shape of the wire construction.

The broken lines in the drawing illustrate environmental matter-
and form no part of the claimed design.
